UNITED STATES PATENT OFFICE.

JULIAN O. ELLINGER, OF NEW YORK, N. Y.

UNIT-BAR FOR CONCRETE CONSTRUCTION.

1,094,843.

Specification of Letters Patent. Patented Apr. 28, 1914.

Application filed January 19, 1912. Serial No. 672,078.

To all whom it may concern:

Be it known that I, JULIAN O. ELLINGER, a citizen of the United States, and a resident of the city, county, and State of New York, have invented certain new and useful Improvements in Unit-Bars for Concrete Construction, of which the following is a specification.

This invention relates to frames for reinforcing concrete and like plastic materials and it has for its object the provision of an effective concrete-reinforcing frame which at the same time may be economically produced.

In the accompanying drawings there are shown several embodiments of the present invention, and these several embodiments are contemplated to be within the spirit and scope of the invention as defined by the subjoined claims.

In said drawings:—Figure 1 is a plan view or side elevation of a very desirable embodiment of the present invention. Fig. 2 is a section on the line 2—2 of Fig. 1. Fig. 3 is a similar section showing a slightly changed form of loop or strap. Fig. 4 also is a similar section, but shows a further slightly changed form of loop or strap. Fig. 5 is a similar section illustrating a different relative arrangement of longitudinal members and straps. Fig. 6 is a similar section illustrating another arrangement of longitudinal members and straps. Fig. 7 is an elevation or plan view exemplifying a further slightly changed relative arrangement of the elements. Fig. 8 is a view, in a plane at right angles to all of the preceding views, illustrating a changed construction of welding projections, with some of the straps broken off to show the welding projections. Fig. 9 is a perspective view of a bar and a part of a strap exemplifying a further embodiment of the present invention.

Similar characters of reference denote corresponding parts in the several views.

Referring to Figs. 1 and 2, which show a most desirable embodiment of the present invention, it will be noted that the frame comprises a longitudinal member, 20 and other longitudinal members 21 and 22, the latter members being arranged in an endwise relation but with a space between their confronting ends and being spaced from

and substantially parallel with the longitudinal member 20 and projecting outward beyond the ends of the latter. Each of these longitudinal members has one of its surfaces formed with a plurality of spaced longitudinal projections, those of the member 20 being marked 20^a, those of the member 21 being marked 21^a and those of the member 22 being marked 22^a. The members 21 and 22 are connected to the member 20 by loops or straps 25 which have side members arranged on opposite sides of the longitudinal member and end members 25^a and 25^b, the latter extending at an angle with said side members and being arranged between the same and forming elements which are integrally united, by being electrically welded, to the longitudinal members 20 and 21, or 20 and 22, at the places defined by the projections hereinbefore referred to.

In the particular exemplification of the invention shown in Figs. 1 and 2, the members 20 and 21 and 20 and 22 are relatively so disposed that their projections are on the opposed surfaces of the parallel spaced members, and the projections extend continuously throughout the lengths of their respective members. The loops or straps 25, moreover, in this particular exemplification of the invention are endless and formed of round rods. With this relative disposition of the parts the loops or straps extend around the longitudinal members and are weldably united to the opposed faces of the latter. The parallel longitudinal members are thus connected to each other by endless straps or loops having members arranged on opposite sides of the frame and integrally united to the outer or opposed surfaces of the longitudinal members. The bars, however, may be relatively so arranged that the straps or loops will be united to confronting surfaces thereof as shown in Fig. 5 or they may be so disposed that the union of the loops or straps will be with corresponding surfaces of the bars, as exemplified by Fig. 6. Again, the straps need not be endless. As shown in Figs. 3 and 5, the straps, which are marked 125 in said figures may be bent into loop form with their ends unsecured to each other; or as shown by Fig. 4, each strap may consist of two separate members 225 arranged on opposite sides of the frame and each having bent ends 225^a welded to the

longitudinal members. Moreover, any of these forms of straps may be made of flat metal instead of round metal. This is exemplified in Figs. 7 and 8, in which the straps are marked 325. The longitudinal members, furthermore, may be provided with separated welding projections instead of continuous welding projections. Fig. 8 exemplifies this, in a form of bar marked 10 320, having welding projections, 320^a, which are separated from each other both longitudinally and transversely of the bar, thereby forming the bar with separated welding projections arranged in pairs. Fig. 9 exemplifies the separated projections as being arranged in a single line, the projection shown in this figure being marked 420^a and the bar marked 420. This figure also exemplifies the use of a strap, having its ends 20 arranged side by side where they are welded to the projections, instead of being abutted, as in Figs. 3, 4 and 5. In Fig. 1, the straps are shown as being at right angles with or perpendicular to the longitudinal members, 25 but they may be arranged in diagonal or inclined positions, as exemplified in Fig. 7.

It will be understood that the foregoing embodiments are merely typical examples of a concrete reinforcing frame characterized 30 by the employment of a plurality of longitudinal members arranged in a spaced relation and connected with each other by a loop or strap having members arranged on opposite sides of the frames and between the longitudinal members and other members which are disposed at an angle to the first mentioned members and are weldably united 35 electrically to the longitudinal members: and that other than the herein particularly 40 illustrated embodiments of the invention may be made without departing from the spirit of the invention as defined by the subjoined claims. Especially will it be understood that any of the straps herein illustrated 45 may be employed with any of the forms of longitudinal members.

A frame constructed in accordance with the present invention is very strong and durable and may be economically produced.

Having now described the invention what I believe to be new and desire to secure by Letters Patent, is—

1. A reinforcing frame for concrete and the like comprising a plurality of spaced bars having welding projections and straps which connect said bars together, each of said straps comprising parts which are arranged on opposite sides of the frame and between said bars and other parts disposed 55 between the first mentioned parts and weldably united to the bars at places defined by said projections.

2. A reinforcing frame for concrete, and the like, comprising a longitudinal bar, other longitudinal bars spaced from each other

and from the first mentioned bar, each of said bars having one of its surfaces provided with welding projections, and straps which connect the first mentioned bar to each of the others each of said straps comprising 70 parts which are arranged on opposite sides of the frame and other parts disposed between the first mentioned parts and weldably united to the bars at places defined by said projections.

3. A reinforcing frame for concrete and the like, comprising a longitudinal bar, other longitudinal bars spaced from each other and from the first mentioned bar, each of said bars having one of its surfaces 80 provided with welding projections, the welding projections on the first mentioned bar being on the opposite side from those on the second mentioned bars, and a series of straps each of which encircles one end of 85 the first mentioned bar and one of the second mentioned bars, and another series of straps which encircles the opposite end of the first mentioned bar and also the other of the second mentioned bars, said straps 90 being weldably united to the several bars at the places defined by said projections.

4. A reinforcing frame for concrete and the like, comprising a longitudinal bar, other longitudinal bars spaced from each 95 other and from the first mentioned bar, each of said bars having one of its surfaces provided with welding projections, straps which connect the first mentioned bar to each of the others, each of said straps comprising parts which are arranged on opposite sides of the frame, and other parts disposed 100 between the first mentioned parts and projecting at right angles thereto and weldably united to the bars at places defined by 105 said projections.

5. A reinforcing frame for concrete and the like, comprising a longitudinal bar, other longitudinal bars spaced from each other and from the first mentioned bar, each 110 of said bars having one of its surfaces provided with welding projections, straps which connect the first mentioned bar to each of the others, each of said straps comprising parts which are arranged on opposite sides of the frame, and other parts disposed 115 between the first mentioned parts and projecting at right angles thereto and extending over one of the longitudinal bars and weldably united to the bars at places 120 defined by said projections.

6. A reinforcing frame for concrete and the like, comprising a longitudinal bar, other longitudinal bars spaced from each other and from the first mentioned bar, each 125 of said bars having one of its surfaces provided with welding projections, straps which connect the first mentioned bar to each of the others, each of said straps comprising parts which are arranged on oppo- 130

site sides of the frame, and other parts disposed between the first mentioned parts and projecting at right angles thereto and extending over the longitudinal bars at each end of the frame and weldably united to the bars at places defined by said projections.

In witness whereof I have hereunto set

my hand in the borough of Manhattan, city and State of New York, this 15th day of January, 1912.

JULIAN O. ELLINGER.

In presence of—

ISABEL R. RICHARDS,
AGNES C. O'CONNELL.
